CLAIM

The ornamental design for a fender receptacle unit for a four wheel vehicle, as shown and described.

DESCRIPTION

FIG. 1 is a left side elevational view of a fender receptacle unit for a four wheel vehicle showing our new design, it being understood that the broken lines are for illustrative purposes only and form no part of the claimed design.

FIG. 2 is a top plan view thereof.

FIG. 3 is a left side elevational view thereof.

FIG. 4 is a rear elevational view thereof.

FIG. 5 is a front elevational view thereof.

FIG. 6 is a bottom plan view thereof.
